UNITED STATES PATENT OFFICE.

JAMES E. JONES AND FRANK C. NEWTON, OF SYRACUSE, NEW YORK; GERTRUDE L. JONES, ADMINISTRATRIX OF SAID JAMES E. JONES, DECEASED, ASSIGNOR TO THE SAID FRANK C. NEWTON.

FUNNEL.

1,425,100.

Specification of Letters Patent. Patented Aug. 8, 1922.

Application filed September 3, 1919. Serial No. 321,418.

To all whom it may concern:

Be it known that we, JAMES E. JONES and FRANK C. NEWTON, citizens of the United States of America, and residents of Syracuse, in the county of Onondaga, in the State of New York, have invented new and useful Improvements in Funnels, of which the following, taken in connection with the accompanying drawings, is a full, clear, and 10 exact description.

This invention relates to certain improvements in bottle fillers in which a funnel having a reduced end adapted to be encircled in the bottle is provided with means for automatically cutting off the flow of fluid from the funnel to the bottle as the latter is filled, the object being to avoid the dangers and waste from overflow, and at the same time to enable the operator to retain in the funnel any excess liquid over that which is required to properly fill the bottle.

Other objects and uses relating to specific parts of the device will be brought out in the following description:

25 In the drawings,—

Figure 1 is an elevation of my improved bottle filler.

Figure 2 is a vertical sectional view of the same and a bottle into which its reduced 30 ends are inserted.

Figure 3 is a sectional view of a modified form of my filler and of a portion of the bottle ready for filling.

Figure 4 is a detail sectional view similar 35 to Figure 3 except that the float is tubular and closed at the top for the trapping of the air therein by the rising liquid, the bottle being omitted.

Devices of this character are particularly 40 useful in transferring liquids from larger to smaller receptacles, as for example, in drug stores or analogous places where liquids are frequently transferred from large stock bottles to smaller bottles, the invention being adapted to prevent overflow of the liquid 45 from the smaller bottle as it is poured into the funnel from a larger bottle so that the operator may determine from the level of the liquid in the hopper whether or not the 50 bottle is filled, such condition being indicated by the rise of the level of the liquid in the funnel which is always opened to view while filling the bottle.

As illustrated in Figures 1 and 2, the filling device comprises a hopper-shaped funnel

—1— having a reduced portion —2— and a still further reduced portion —3— the latter being provided with a flange —4— some distance below the reduced portion —2— and in fixed relation to the body of the funnel. 60

Surrounding the reduced portion —3— below the flange —4— is a ring or plate —5— of greater diameter than that of the mouth of the bottle as —A— upon which it is adapted to rise when the funnel is placed 65 in operative position for filling the bottle.

One side of the ring is provided with a post —6— passing through an aperture —7— in the adjacent portion of the flange —4—, the upper end of said post being enlarged 70 to form a head —8— above the flange —4— to allow limited vertical movement of the plate —5— relatively to the flange when the funnel is lifted away from the mouth of the bottle as shown in Figure 1. 75

The opposite side of the plate —5— is provided with an upstanding flange —9— having an aperture —10— for receiving the adjacent portion of a weighted arm —11—.

This arm —11— is pivoted at —12— to 80 an upstanding flange —13— on the same side of the reduced portion —3— as the upstanding flange —9— of the plate —5—, the inner end of said weighted arm being provided with an aperture —14— for receiving 85 the upper end of a vertically movable rod —15— which is enlarged at the top to just above the adjacent portion of the arm —11— to limit the downward movement of the rod —15—. 90

A tubular float —16— is provided with a tapered upper end —17— constituting a valve which is movable into and out of engagement with a valve seat —18— on the lower end of the tubular extension —3— of 95 the hopper to control the flow of the liquid from the hopper to the interior of the bottle.

The upper end of the tube —16— is closed by the valve —17— while the lower end of the same tube is opened so that as the liquid 100 level in the bottle rises, it will trap the air in the tube —16— and cause said tube to float.

This tubular float is provided with lateral apertured lugs —19— for receiving the rod —15—, the latter having its lower end enlarged to form a head or limiting stop to limit the downward movement of the float when the head at the upper end is resting upon the arm —11—. This rod, therefore, 105 serves as a guide for the tubular float —16— 110

to register it with the outlet or valve seat 18 in the tubular extension —3—.

This float is also provided with a central upwardly projecting stem —20— extending 5 through a central aperture in a perforated disk —21— which is seated in the bottom of the reduced portion —2— near its junction with the reduced portion —3—.

The upper end of the stem —20— above 10 the plate —21— is provided with a limiting stop —22— which is adapted to engage the upper face of the plate —21— to additionally limit the downward movement of the float —16— away from the valve seat 15 —18—.

It will be observed upon reference to figure 2 that the rod —15— and upstanding flange —9— of the plate —5— engage the weighted arm —11— at opposite sides of 20 its pivot —12—, the weight of said arm being preferably secured to the outer end of the arm —11— beyond the upstanding flange —9—.

When the filler is lifted from the mouth 25 of the bottle so as to disengage this plate —5— therefrom, the weighted end of the lever —11— is sufficient to overcome the weight of the tubular float —16— and parts carried thereby with sufficient force to close 30 the valve —17— against the seat —18— and to thereby retain any liquid which may remain in the funnel against further discharge.

On the other hand, when the filler is 35 placed upon the mouth of the bottle with the plate —5— resting thereon, the weight of the entire filler is sufficient to elevate the plate —5— until it bears against the under side of the flange —4— by which operation 40 the upstanding flange —9— exerts a lifting action upon the weighted end of the lever —11— thereby depressing the inner end of said lever and allowing the float —16— to drop away from its seat which in turn allows 45 the liquid to flow through the perforated plate —21— and reduced portions —2— and —3— of the funnel into the bottle —A—.

The weight of the float —16— and its 50 counterweighted lever —11— is adjusted so that by the time the liquid level has approached sufficiently close to the mouth of the bottle to fill the same without overflowing, it will have elevated the float —16— independently of the weighted lever sufficiently 55 to close its valve —17— against the seat —18— thus automatically preventing further discharge of the liquid from the funnel into the bottle.

60 The bottle now having been filled, the funnel with the remaining liquid therein is lifted from the mouth of the bottle while at the same time the weight of the outer end of the arm —11— and plate —5— will cause 65 the elevation of the inner end of the lever

against the upper head of the guide rod —15— to keep the valve closed while the funnel is being removed from the bottle whereupon the residue liquid in the hopper may be restored to the original receptacle. 70

In Figure 3, I have shown a modified construction of filler consisting of a funnel —1— having a reduced portion —2'— at its apex provided with suitable outlets —3'—, the upper end of the tubular extension —2'— constituting a valve seat —18'—.

The intermediate portion of the tubular extension —2'— is also provided with an additional valve seat —23— for cooperation with a float valve presently described. 80

A tubular member —24— has its upper end slidably mounted upon the tubular extension —2'— and provided with an enlarged annular flange —25— adapted to raise upon the mouth of the bottle as —A— when the filler is adjusted for use, the lower end of said tubular member —24— being provided with a transverse partition —26—.

A float —27— of cork or other suitable material is provided with a central lengthwise reinforced stem —28— extending beyond the opposite ends of said float, the upper end of the stem being provided with a valve —29— for cooperating with the seat —18'— to prevent the discharge of the liquid from the funnel when the latter is removed from the bottle. 90

The lower end of the stem —28— is guided in a central aperture —30— in the partition —26— and is provided with adjustable limiting stops —31— and —31'— in spaced relation vertically to engage respectively the upper and lower faces of the partition —26— allowing a limited vertical movement of the stem and its float —27— sufficient to permit the upper end of the float which constitutes a valve to close against the seat —23—. When the float is elevated by the rise of the level of the liquid in the bottle the partition and side walls 100 of the tubular member —24— are preferably perforated to permit the entrance of the liquid of the bottle into said tube for lifting action upon the float to close it against the valve seat —23—, it being understood that the weight of the float is adjusted so that it will close against its seat —23— when the level of the liquid approaches the mouth of the bottle and before the liquid overflows. 105

The reduced portion —2'— is provided with an annular flange —33— against which the upper end of the tubular member —24— abuts when the funnel is placed in operative position upon the bottle with the plate —24— resting on the mouth thereof. 115

Under these conditions the bottle being empty, the upper stop —30— on the rod —28— will rest upon the upper face of the transverse partition —26— and is adjusted 120

so as to hold the valve —29— and upper end of the float —27— slightly away from their respective seats —18'— and —23'— to establish a free opening for the liquid 5 from the hopper into the bottle.

Now, if the liquid is poured into the hopper it will, of course, flow into the bottle past the opened valve and when the level of the liquid approaches the mouth of the bottle 10 before it overflows it will lift the float —27— and its stem —28— sufficiently to close it against the valve seat —23— to prevent further flow of the liquid from the funnel to the bottle, it being understood that 15 the lower stop —31'— is adjusted with sufficient clearance to allow the closing of the float.

When the bottle is thus filled the funnel may be lifted therefrom which allows the 20 weight of the tube —24— to slide along the reduced portion —2'— away from the flange —33— and causes its partition —26— to engage the stop —31'— and close the valve 29 against its seat —18'— to retain 25 any residue liquid in the funnel while the latter is being removed from the bottle.

In Figure 4 which is somewhat similar to Figure 3, the float consists of a metal tube —27'— open at the bottom and closed at 30 the top to permit the rising liquid to trap the air therein, said air containing float being balanced in such manner as to cause its upper end to close the outlet passage from the hopper —1'— when the bottle is 35 substantially filled.

What we claim is:

1. In a bottle filler, the combination of 40 a funnel having an outlet tube adapted to be inserted in the mouth of the bottle to be filled and provided with a flange, a plate movable lengthwise of the outlet tube at the

underside of the flange for engagement with the mouth of the bottle when the filler is placed in operative position thereon, said plate being removed toward and against 45 the flange by said engagement, a float valve for opening and closing said outlet, means for automatically closing the valve when the filler is removed from the bottle, and means actuated by the plate for operating the 50 first named means to allow the valve to open by its own weight when the filler is supported upon the bottle, said float-valve being operable by the rising of the liquid in the bottle to close the outlet independently of 55 the first and second named means.

2. In a bottle filler, the combination of a funnel having an outlet tube adapted to be inserted in the mouth of the bottle to be filled, said tube being provided with a flange, 60 a plate loosely attached to the flange for engagement with the mouth of the bottle when the filler is placed thereon, a float-valve for opening and closing the outlet and adapted to open by its own weight and 65 to close by the rising of the liquid in the bottle when the filler is in operative position, and means including a weighted lever fulcrumed on said flange for automatically closing the float-valve when the filler is removed from the bottle, said plate having 70 means for engaging and operating the weighted lever against the action of the weight, to allow the valve to open when the filler is in operative position on the bottle. 75

In witness whereof we have hereunto set our hands this 27th day of August 1919.
